UNITED STATES PATENT OFFICE.

RALEIGH L. FRENCH, OF NEW YORK, N. Y.

SIGNAL DEVICE.

Application filed September 23, 1922. Serial No. 591,342.

To all whom it may concern:

Be it known that I, RALEIGH L. FRENCH, a citizen of the United States, and resident of New York, in the county of New York and State of New York, have invented certain new and useful Improvements in Signal Devices, of which the following is a specification.

The invention relates to improvements in signal devices adapted to be attached to motor vehicles for indicating the relative position and intended movement thereof with respect to the road.

Among the objects of the present invention are means for directing the rays of light from a single lamp to constitute a rearwardly projecting tail or safety light, a forwardly projecting parking light, and the illumination both for a license plate and a pair of signal arms; also to provide an arm structure adapted to readily reflect the light and to afford strengthening means therefor and a protection for the illuminated face against the action of the weather; also to provide means for operating the arms independently of each other and to hold the same in the desired position of observation.

For further comprehension of the invention, and of the objects and advantages thereof, reference will be had to the following description and accompanying drawings, and to the appended claims in which the various novel features of the invention are more particularly set forth.

Figure 1 of the drawings is a face view showing the device in operative position as observed from a following car. Figure 2, a vertical section showing the relation of the several operating parts with respect to one another. Figure 3, a horizontal section taken on the line 3—3, Fig. 2. And Figure 4 is a view, partially in section, of the operating means for the signal arms, as controlled by the driver of the car.

In the drawings, numeral 10 designates a cylindrical case, having at its lower end a detachable head 11, forming the upper part of a short standard 12, the lower flange of which is adapted to be fixed to the upper face of a rear-wheel mud-guard, indicated by the line 13. At its upper end the casing is formed with an integral head 14, which merges into the walls of a lamp-chamber 15 having a rearwardly extending tail-light passage provided with the lens 16, the chamber being also provided with lenses 17 and

18 disposed to forwardly project the rays of light from the lamp 19, suitably arranged within the chamber and connected with the electric wire 20. The rays of light from the lamp 19 are furthermore divided and projected through the passage 21, formed through the lower wall of the projecting section of the lamp chamber, the passage being covered by the transparent facing 22, through which the rays of light 19a are directed upon the license plate 23, the latter being conveniently fixed upon the casing 10 by the brackets 24. For jointly directing the rays of light and for protecting the working parts of the device against the weather, the casing is provided with the upper guard wall 25 and the side walls 26, the former wall being joined at its outer end to the case by the upright stop member 27.

The upper head 14 of the casing is provided with a hub 28, in which is rotatably mounted a tubular shaft 29, loosely surrounding the solid shaft 30, the latter being rotatably journaled at its lower end in the standard 12. To the upper end of the tubular shaft 29 is fixed a signal arm 31 and to the corresponding end of the solid shaft 30 is also fixed a similar arm 32, the hub connections thereof being disposed in off-set relation on the arms to permit the projecting ends of the latter to assume a common horizontal plane of motion.

For effecting the independent movements of the signal arms, their respective shafts are fixedly secured at their lower ends with the grooved wheels 33 and 34, respectively provided with the helical springs 35 and 36, one end of each spring being fixed to its respective wheel while the opposite end of the spring is held by the abutment 37, fixed to the interior of the case, the coils of the springs being arranged to rotate and normally hold their respective signal arms in a closed or unobserved position against the stop member 27. For operating the signal arms into open positions of observation, their respective shafts are rotated against the action of the springs by means of the flexible lines 38 and 39, one of the ends thereof being fixed respectively to the grooved wheels 33 and 34, while their opposite ends are attached to the handle rods 40 and 41, slidable in the respective tubes 42 and 43. The tubes are connected together side by side to one end of a coupling 44, the opposite end of the latter being also connected to a flexible

tube 45 arranged to inclose and guide the flexible lines 38 and 39 from the signal case to the point of manual operation. A bracket 46 is fixed to the tubes 42 and 43 and is 5 provided with screw holes 47 by means of which the tubes may be fixed at a convenient point for operating the handle rods. For holding the signal arms in their outward positions of observation, the tubes 42 and 10 43 are each provided with a bayonet slot having a longitudinally extending portion 48 merging into a laterally extending terminal stop section 49, the slots being arranged to slidably receive the projecting pins 50, 15 fixed in the handle rods 40 and 41, the outer ends of the rods being shaped to form finger grips 51.

In Fig. 4, the handle rods 40 and 41 are 20 shown respectively in their outward and inward positions, corresponding with the open and closed positions of their connected signal arms, the operations of which are similarly made either separately or jointly. As indicated in Figs. 2, 3 and 4, the arm 32 is 25 shown in its closed position, held against the stop 27 by means of the spring 36 acting through the wheel 34 and shaft 30, and for operating this arm into open position the handle rod 41 is drawn outwardly and turned 30 within its tube into the position indicated by dotted lines and held therein by the pin 50 in its engagement with the lateral stop slot 49. This outward movement of the handle rod is transmitted to the arm through 35 the line 39, wheel 34 and shaft 30, and against the opposite rotative action of the spring 36. The closing movement of the arm is made by simply turning the handle rod in the opposite direction until its pin 40 50 engages the longitudinal slot 48, whereupon the action of the spring 36 will cause the arm to be automatically returned to its closed position. It will thus be obvious that 45 either signal arm may be independently operated into open position to indicate the direction in which the car is about to turn, or both arms may be thus operated together by engaging both finger grips and outwardly 50 drawing the handle rods at one time and jointly turning them in one direction, the stop slots in the tubes being positioned to receive the rod pins in this turning movement and hold both arms extended to indicate a stop signal for a following car.

To provide signal arms readily observable 55 under all weather conditions, the faces thereof are left open, and are sectionally disposed in angular relation in each arm, as indicated at 31^a, 31^b, 32^a and 32^b, to permit the rays of light from the lamp to be distributed by reflection along their entire length. At the 60 top edges of the arms, rearwardly projecting flanges or ribs 52 are provided which serve to protect the faces of the arms from the weather and also act during the forward

movement of the car as draining ledges from which the rain is automatically discharged.

What I claim as new and desire to secure by Letters Patent, is:

1. In a signal device for a motor car, a 70 casing therefor having a lamp, a light passage in the casing leading from the lamp toward the forward end of the car, and a signal arm on the casing movable into open and closed positions, the open position of the 75 arm intercepting the rays of light from said passage and deflecting them rearwardly of the car and the closed position thereof permitting the rays of light to project forwardly of the car. 80

2. In a signal device for a motor car, a casing therefor having a lamp, light passages in the casing leading from the lamp toward the forward end of the car, and a pair of signal arms on the casing movable 85 into open and closed positions, the open positions of the arms intercepting the rays of light from said passages and deflecting them rearwardly of the car and the closed positions thereof permitting the rays of light to project forwardly of the car. 90

3. In a signal device for a motor car, a casing therefor having a lamp, means on said casing for supporting a license plate, a light passage leading from the lamp toward 95 the license plate, a light passage in the casing leading from the lamp toward the forward end of the car, and a signal arm on the casing movable into open and closed positions, the open position of the arm intercepting the rays of light from said passage and deflecting them rearwardly of the car and the closed position thereof permitting the rays of light to project forwardly of the car. 100

4. In a signal device for a motor car, a casing therefor having a lamp, means on said casing for supporting a license plate, a light passage in the casing leading from the lamp toward the license plate, a light passage 110 in the casing leading from the lamp rearwardly of the car and adapted to serve as a tail-light signal, a light passage in the casing leading from the lamp toward the forward end of the car, and a signal arm on the casing movable into open and closed positions, the open position of the arm intercepting the rays of light from said passage and deflecting them rearwardly of the car and the closed position thereof permitting the rays of light to project forwardly of 115 the car. 120

5. A signal arm having angularly arranged open reflecting faces adapted to receive and distribute light, a cover flange at the upper edges of said reflecting faces, and a supporting hub for said arm. 125

Signed at New York, in the county of New York and State of New York, this 14th day of August, A. D. 1922.

RALEIGH L. FRENCH.
